UNITED STATES PATENT OFFICE.

WALTER J. LEHMAN, OF DETROIT, MICHIGAN, ASSIGNOR TO BRIGGS MANUFACTURING COMPANY, OF DETROIT, MICHIGAN, A CORPORATION OF MICHIGAN.

FIXTURE FOR RIVETING MACHINES.

Application filed April 27, 1925. Serial No. 26,221.

This invention relates generally to riveting machines and refers more particularly to the anvils and cooperating pistons of tubular riveting machines.

One of the essential objects of the invention is to provide a construction of this type in which the piston is detachably mounted in a suitable support and is normally held in operative position by means of air under pressure.

Another object of the invention is to provide a construction of this type in which a bushing serves as a guide for the piston and has a head that constitutes an anvil and that is adapted to receive a projection of the piston.

Another object is to provide a simple and compact construction in which the piston is readily replaceable.

A further object is to provide a construction that is strong and durable and can be manufactured at a comparatively low cost.

With the above and other objects in view, the invention consists of certain novel features of construction, combination and arrangement of parts as will be more fully described and particularly pointed out in the appended claims.

In the accompanying drawing:

Figure 1 is a fragmentary side elevation of a fixture embodying my invention.

Figure 2 is a fragmentary side elevation of the block.

Figure 3 is a top plan view of the block.

Figure 4 is an end view of the block.

Figure 5 is a top plan view of the bushing.

Figure 6 is a sectional view taken on the line 6—6 of Figure 5.

Figure 7 is a detail view of the piston.

Figure 8 is a side elevation of the nut.

Figure 9 is a bottom plan view of the nut.

Figure 10 is a detail side elevation of the spring.

Referring now to the drawing, the numeral 1 designates a block for supporting a piston 2 which is adapted to cooperate with the usual driver 3, and an anvil to be hereinafter described, for riveting together a plurality of metal plates 4 and 5 respectively, constituting the "work." As shown, the block is preferably wedge shape in form and is rigidly secured by means of the bolt 6 to the laterally projecting arm 7 of the standard of the riveting machine. If

desired, suitable dowels 8 may be used for accurately positioning the block 1 upon the arm 7.

The piston 2 may be any shape desired and may be formed of any suitable material. As shown, the body portion of the piston is preferably cylindrical in form and is provided at its upper end with the central cylindrical projection 9 for engagement with a suitable rivet 10.

In order that air under pressure may be used to hold the piston 2 in operative position, the block 1 is preferably provided at its outer end with the vertical bore 11 in which the piston 2 is adapted to reciprocate and for guiding the piston, I preferably provide a tubular bushing 12 that has a press fit within the bore 11. As shown, this bushing 12 receives the body portion of the piston and is provided at its upper end with a flanged head 13 having a central aperture 14 for receiving the projection 9 of the piston. This head 13 also preferably constitutes an anvil and for this purpose is provided with a cup-shaped recess 15 that surrounds the central aperture 14 and is adapted to receive the lower end portion of the rivet 10. The lower end of the bushing 12 preferably terminates short of the lower end of the bore 11 and preferably cooperates with a suitable nut 16 to form a passage 17 for air. As shown, this nut 16 threadedly engages the lower walls of the bore 11 in the block and is preferably provided with a central frusto-conical projection 18 which serves as a seat for the body portion of the piston 2 when the latter is in lowered position. Any suitable means such as the straight free end portion 19 of the arcuate shaped spring 20 secured to the base 21 of the recess 22 in the lower face of the block 1 may be used to engage the radial slots 23 in the lower face of the nut 16 to prevent the latter from working loose or becoming accidentally disengaged from the block 1.

In order that air under pressure may be conveniently conveyed to the bushing 12 to actuate the piston 2, the block 1 is preferably provided at one side intermediate the ends thereof with a transversely extending bore 24 constituting an inlet passage, and is provided with the longitudinally extending bore 25 that connects the inlet passage 24 with the passage 17 between the bushing 12 and the block 1.

and nut 16. Any suitable means (not shown) may be used to convey the air under pressure from a suitable source of supply to the inlet passage 24. This means may also be provided with a valve for regulating the supply.

In the process of manufacture, a suitable drill (not shown) is used to bore the lateral passage 25. To accomplish this the passage 25 is started at the outer end of the block 1, thus a passage 27 is formed between the vertical bore 11 and the outer end of the block; however this passage 27 is closed by a suitable block before the device is put into operation.

In use, the desired quantity of air under pressure may be supplied to the passage 17 between the nut 16 and bushing 12, to normally hold the projection 9 of the piston in projected position. To prevent this air from displacing or otherwise affecting the rivets 10 used to connect together the plates 4 and 5 respectively or other work, the bushing 12 is preferably provided adjacent to the head 13 with a radial bore 30 that registers with a suitable outlet passage 31 in the block 1. Thus the air will be discharged laterally. Should it be desired to replace the piston 2, the spring 20 is first disengaged from the nut 16, whereupon the latter may be readily removed from the bore 11 to permit the piston 2 to drop from the bushing 12. A new or substitute piston may then be inserted into the bushing 12 and the nut 16 and spring 20 re-engaged as before.

While it is believed that from the foregoing description the nature and advantages of the invention will be readily apparent, I desire to have it understood that I do not limit myself to what is herein shown and described, and that such changes may be resorted to when desired as fall within the scope of what is claimed.

What I claim as my invention is:

1. In a device of the class described, the combination with a piston having a projection for engagement with a rivet, of a block having a bore receiving the piston, a passage for supplying air under pressure to the bore to actuate the piston, and a radial passage, a bushing within said bore surrounding said piston and having a head constituting an anvil provided with an aperture for receiving the projection of the piston, said bushing also having a radial passage registering with the radial passage aforesaid for discharging air laterally so that it will not affect the rivet.

2. In a device of the class described, the combination with a piston for engagement with a rivet, of a block having a bore re-

ceiving the piston, and a longitudinally extending air supply passage, a bushing surrounding the piston within the bore and terminating short of the lower end of said bore, a closure for the lower end of the bore spaced from the bushing to provide an air passage in communication with the air passage aforesaid.

3. In a device of the class described, the combination with a piston for engagement with a rivet, of a block having a bore receiving the piston, a bushing surrounding the piston within the bore terminating short of the lower end of the bore, and a closure for the lower end of the bore spaced from the bushing and having a portion constituting a seat for the piston when the latter is in lowermost position.

4. In a device of the class described, the combination with a piston for engagement with a rivet, of a block having a bore receiving the piston, means associated with said block for conveying air under pressure to the piston for actuating the same, a bushing surrounding the piston within the bore, a closure for the lower end of the bore spaced from the bushing and having a portion constituting a seat for the piston when the latter is in lowermost position, and a yieldable element secured to the block having a portion engaging slots provided in said closure for preventing the latter from becoming accidentally disengaged from the block.

5. In a device of the class described, the combination with a piston having a projection for engagement with a rivet, of a block having a bore receiving the piston, a passage for supplying air under pressure to the bore to actuate the piston, a bushing surrounding the piston within the bore and terminating short of the lower end of said bore, a nut threadedly engaging the lower walls of the bore spaced from the bushing and having a portion constituting a seat for the piston in one position thereof, and a yieldable member detachably secured to the block having a portion engageable with the nut to prevent accidental displacement thereof.

6. In a device of the class described, the combination with a piston for engagement with a rivet, of a block having a bore receiving the piston and having a radial passage, a passage for supplying air under pressure to the bore to actuate the piston, and a bushing within said bore surrounding said piston and having a radial passage aforesaid for discharging air laterally so that it will not affect the rivet.

In testimony whereof I affix my signature.

WALTER J. LEHMAN.
